UNITED STATES PATENT OFFICE.

EDWARD R. INMAN, OF FRANKLIN, PENNSYLVANIA.

SECTION LINER.

Application filed November 21, 1925. Serial No. 70,566.

This invention relates to improvements in that class of drafting instruments that are known as section liners, and has for its object the attainment and provision of the following objects and advantages:

1. The provision of a micrometric adjusting device for the stop which determines and limits the extent of movement of the spacing lever and its actuation of the pen-guide or rule.

2. The provision of a micrometric adjusting device for the stop of the spacing lever so adapted that each successive actuation and movement of the ruler may be caused to be infinitesimally, or any suitable degree, greater or less than the preceding movement, as in and for the purpose of shading curved surfaces.

3. The provision of a positive locking device for the stop of the spacing lever so that the extent of actuation of said lever may be caused to be exactly the same at each movement thereof, and whereby the instrument is made suitable for the accurate graduation of measuring scales and the like.

4. The provision of needle-points for securing the bed of the instrument in its service position, which points are so inserted as to be positively secured in position against accidental displacement and, at the same time, are readily and quickly removable for repair or replacement.

5. To provide a section liner that will meet the requirements of the engineering profession in respect to construction, accuracy of work, scope of utility and function, improvement in appearance of work, and to supply an instrument that may be sold at a reasonable price.

40 The construction whereby I am enabled to attain said objects is clearly illustrated in the accompanying drawings in which:

Fig. 1 is a plan view of my improved section liner.

45 Fig. 2 is a section on line II—II of Fig. 1.

Fig. 3 is a section on line III—III of Fig. 1.

Fig. 4 is a section on line IV—IV of Fig. 1, and

50 Fig. 5 is a section on line V—V of Fig. 1.

The construction shown in said drawings is substantially as follows:

The instrument is provided with a bed 1, which is preferably composed of wood, though bakelite would be a very suitable ma-

terial for such use; while metal might be used, it has not been found suitable for this class of instruments.

Said bed carries at its upper end the laterally-projecting rod-bearings 2, 3, which are 60 preferably formed as an integral structure.

Said bed also carries at its lower end the rod bearing 4, said bearings 2, 3 and 4 being adapted for the reception of the longitudinally movable rod 5 which is arranged and 65 adapted to carry the pen-guide or ruler 6, which is usually a straight-edge but a guide of any desired outline may be employed.

Mounted upon said rod 5 and positioned between said guides 2 and 3 is a spacing lever 70 7 which is adapted to frictionally engage said rod 5 in such manner as to actuate and move same in the downward direction together with the ruler 6 carried by said rod.

Positioned above the guide 2 is a frictionally-engaging detent 8 which engages and is 75 adapted to normally prevent said rod from moving in the upward direction,—that is, in the direction reversely to the direction of actuation of said lever 7.

As indicated in the preamble of the subjoined claims, the elements of this construction thus far enumerated, are not broadly new, but have, in certain forms and modes of arrangement, been known and used for upwards of thirty years: The particular form

80 of the bearings 2, 3 and 4, however, together with a portion of the functions they perform in my improved instrument I believe to be novel.

90 For the purpose of limiting and determining the extent of actuation of rod 5 by said spacing lever 7. I have supplied my improved instrument with a novel device consisting of the combination of the cam-shaped stop 9 with a micrometric adjusting device 95 consisting of the toothed wheel 10 and a co-operating screw 11, said wheel and screw being in the nature of a worm gear. Said screw 11 is provided with an arbor which is 100 revolvably mounted in the bearing 12, which arbor and screw 11 are operable by means of the thumb-wheel 13. Said bearing 12 is split longitudinally in axial alinement with said screw arbor and is so constructed that 105 said screw arbor may be firmly clamped by and within said bearing for the purpose of locking said screw 11 and the thereby-engaged wheel 10 together with said stop 9, to which said wheel 10 is rigidly secured in 110

any desired position of adjustment, whereby a uniform movement of said lever 7 and a correspondingly uniform actuation of said ruler 6 may be secured at every actuation of said lever, as in, and for the purpose of accurately graduating measuring scales, and like work, as well as in uniformly-spaced lines in cross-hatching.

A clamping-screw 14 is provided for the purpose of producing said clamping action of said bearing 12 in relation to the arbor of said screw 11.

This instrument is adapted to be retained in its service position by means of needle points which are arranged to project slightly below the under face of said bed 1; said needle points are indicated by the reference numeral 15, and attention is especially directed to Fig. 5, said points being indicated in dotted lines in Fig. 1. I have devised an improved method of inserting said needle points, whereby the objections heretofore obtaining to the use of needle points is obviated; said objection is found in the liability of the points to be upwardly displaced or pushed back from their service position when the instrument is placed upon the drafting board, and the difficulty of replacing them when they become either thus displaced or the points broken off. In my improved method of mounting said points, said objections are obviated in the following manner:

Under each of the plates 16 and 17, which are removably secured in position by means of the screws 18, is located an insert 19 which extends through bed 1, is composed preferably of cork or soft wood and has the shape of a truncated cone with the smaller end thereof positioned downward. The seat for said cone, as previously stated, extends through said bed 1 and has a shape corresponding to that of said insert. By means of said shape of the inserts, they are adapted to be retained securely in position by means of their respectively-adjacent plates 16 and 17. Said needle-points extend through said inserts, and their upper ends bear against their respective plate, 16 or 17, and they are thus prevented from being pushed upward from their service position.

I prefer to form the rod-bearings 2 and 3 integrally with the plate 17, and the rod-bearing 4 integrally with plate 16, for the sake of economy of manufacture, accuracy of alinement, neatness and strength, as well as precision and facility of operation.

Detent 8, at its inner end, is in loose engagement with an adjacent portion of said plate 17; its outer portion is provided with a hole through which rod 5 passes at a comparatively loose fit. Said outer end of said detent is free to have a certain amount of swinging movement in the direction of the longitudinal movement of said rod 5. Between said detent and the adjacent face of said bear-

ing 2, and encircling said rod, is interposed a compression spring 20, the reaction of which is such as to actuate said detent to an angular position, as indicated in Fig. 1, and thus to angularly or frictionally engage said rod as to normally prevent its movement in the upward direction, but freely permits its downward actuation by means of said lever 7. When it is desired to restore the ruler 6 to its upward position, and to actuate rod 5 accordingly, this may be readily accomplished by placing said detent and holding same in a position of true perpendicularity to the axis of said rod, whereupon, said rod will freely slide through same in an upward direction.

One of the particular advantages of my improved section liner is the facility and accuracy whereby drawings representing cylindrical and curved surfaces may be shaded with it: When such work is being done, the distance between the successive shade lines may be easily and quickly caused to be infinitesimally greater or less by a manipulation of the thumb-wheel 13 previously to each actuation of the spacing lever 7. Spacing of this kind cannot be produced by means of a section liner which employs a rack or toothed bar in place of the rod 5, neither can it be practically produced by means of an eccentric stop which is not actuated by means of a screw.

Attention is hereby directed to my co-pending application Serial Number 266,410, filed March 31, 1928 for a more complete description of the placement pin structure illustrated in Fig. 5.

I claim the following:

1. In a section liner comprising a bed, a longitudinally-moveable rod carried by said bed, a ruler carried by said rod, an actuating lever for said rod arranged to frictionally engage and to longitudinally actuate the rod in one direction and means on the bed arranged to normally prevent movement of said rod reversely to said actuation; the combination with the foregoing of a cam-shaped stop on the bed arranged and adapted to gauge the extent of actuation of said lever and the thereby-engaged rod, a worm gear mounted on the bed adapted to micrometrically actuate said stop so as to vary at will and by infinitesimal degrees the extent of successive actuations of said lever, and means adapted to lock said stop in any desired position whereby the extent of successive actuations of said lever are caused to be uniform, as in the graduation of measuring scales.

2. In a section liner comprising a bed, a longitudinally-moveable rod carried by said bed, a pen-guide carried by said rod, an actuating lever for said rod extending over said bed arranged to frictionally engage and longitudinally actuate the same in one direction and means engaging said rod and said bed

arranged to normally prevent the movement of said rod reversely to said actuation; the combination with the foregoing of a cam-shaped stop arranged to micrometrically 5 gauge the extent of successive actuations of said lever and the thereby-engaged rod, as in the shading of curved and cylindrical surfaces, a worm gear adapted to micrometrically 10 actuate said stop at will intermediate the successive movements of said lever, means arranged to lock said stop in any desired position for the purpose of insuring a uniformity of extent of successive actuations of said lever, as in the graduation of measuring 15 scales, and means retaining said bed in its service position whereby precision work of the character set forth is facilitated.

3. A section liner comprising a bed, a longitudinally movable rod carried by said 20 bed, a ruler carried by said rod for movement therewith and an actuating lever for and carried by said rod; the combination with the foregoing of an infinitesimally-adjustable stop for said lever whereby its movements 25 may be varied at will by infinitesimal degrees said stop comprising a cam-faced mem-

ber pivotally carried by said bed with its cam-face arranged for contact by said lever, a worm wheel secured to said member for actuating same, a worm revolubly carried by 30 said bed in mesh with said wheel, and means for locking said worm against revolubility for the purpose set forth.

4. A section liner which comprises among 35 its elements, a bed, plates, each having one or more rod-bearings carried upon the upper face of said bed in ready removability therefrom, a rod mounted and having longitudinally movement in said bearings, a pen-guide 40 carried by and movable with said rod, means carried by said rod adapted to longitudinally actuate same in one direction, and needle-points beneath said plates inserted through said bed with their points projecting through the under face of the bed to hold same in its 45 service position; said plates arranged to retain said points in position, and the removability of said plates being for the purpose of permitting removability and renewability of 50 said points.

In testimony whereof I affix my signature.
EDWARD R. INMAN.
